UNITED STATES PATENT OFFICE.

JACQUES SCHNEIDER, OF SOLOTHURN, ERNST HÜRLIMANN, OF ZUCHWIL, AND
FREDERIC BILLON, OF SOLOTHURN, SWITZERLAND, ASSIGNEES TO THE
FIRM SCINTILLA, OF SOLOTHURN, SWITZERLAND.

HIGH-TENSION DISTRIBUTER FOR MAGNETO-ELECTRIC IGNITION-MACHINES.

1,349,299.

Specification of Letters Patent. Patented Aug. 10, 1920.

Application filed August 22, 1919. Serial No. 319,234.

To all whom it may concern:

Be it known that we, JACQUES SCHNEIDER, a citizen of the Swiss Republic, residing at Solothurn, Switzerland, ERNST HÜRLIMANN, 5 a citizen of the Swiss Republic, residing at Zuchwil, Canton of Solothurn, Switzerland, and FREDERIC BILLON, a citizen of the Swiss Republic, residing at Solothurn, Switzerland, have invented certain new and 10 useful Improvements in High-Tension Distributers for Magneto-Electric Ignition-Machines, of which the following is a specification.

In magneto-electric ignition machines it 15 has become customary to employ an arrangement in which the high tension distributor rotates around an axis situated vertically over and parallel to the axis of rotation of the rotating parts of the ignition machine. 20 Both parts are mounted in a common casing. According to this invention the fixed current-collecting brushes are embedded in insulating cheeks which are removably inserted in suitable apertures on both sides of 25 the distributor and which contain also the insertion apertures and the connecting clips or terminals for the sparking plug leads.

Figure 1 of the accompanying drawings shows a cross section through the distributor 30 built up on the magnet dynamo.

Fig. 2 shows a side elevation of the distributor casing.

Fig. 3 shows the distributor casing in plan.

The rotating part *b* of the ignition machine moves in the lower portion of the casing *a*. The cylindrical high tension distributor *c* which is made of insulating material and contains the metal segments *e* that 40 are electrically connected to the current supply contact *d*, rotates vertically above the said rotating part. The distributor space is separated by the insulating wall *f* from the lower portion of the machine, and particularly from the rotor *b*. On both sides of 45 the cylinder *c* the distributor space is closed by the two insulating cheeks *g* in which the current-collecting brushes *h* are inserted. These brushes are in electrical connection 50 with the terminal screws *i* for the connection of the sparking plug leads, and project into the insertion apertures *o* that are provided for this purpose. The insulating cheeks *g* bear upwardly against a metal in-

termediate piece *k* which is connected to the 55 casing *a* and which serves for stiffening and protecting purposes. These cheeks are covered at the front end of the machine by the bearing end plate *l*, and are held in their position by loop-shaped fixing springs *n* 60 capable of turning around the axis *m*.

What we claim is:—

1. In a high tension distributor in magneto-electric ignition machines, in which the distributor rotates vertically above and 65 parallel to the axis of rotation of the rotor of the machine in the same casing of the machine, the combination with the stationary current-collecting brushes, of two removable insulating cheeks in which said 70 brushes are embedded, said insulating cheeks closing both sides of the distributor space, and also containing the insertion apertures and connecting clips or terminals for the 75 sparking plug leads.

2. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing 80 both sides of the distributor space, and also containing the insertion apertures and connecting clips or terminals for the 85 sparking plug leads, and an insulating wall separating the distributor space from the rotor of the machine. 90

3. In a high tension distributor in magneto-electric ignition machines, in which the distributor rotates vertically above and parallel to the axis of rotation of the rotor of the machine in the same casing of the machine, the combination with the stationary current-collecting brushes of two removable insulating cheeks in which said brushes are embedded, said insulating cheeks closing 95 both sides of the distributor space, and also 100 containing the insertion apertures and connecting clips or terminals for the sparking plug leads, and a metallic intermediate member connected to the casing, for stiffening said insulating cheeks at their tops. 105

4. In a high tension distributor in magneto-electric ignition machines, in which the distributor rotates vertically above and paral-

lel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 5 sparking plug leads, and a bearing end plate of the machine, covering said insulating cheeks at their front ends.

5. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 10 sparking plug leads, and a bearing end plate of the machine, covering said insulating cheeks at their front ends.

15. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 20 sparking plug leads, and a bearing end plate of the machine, covering said insulating cheeks at their front ends.

pivoting around an axis at right angles to the distributor axis, for holding said insulating cheeks in their places.

6. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 25 sparking plug leads, and a bearing end plate of the machine, covering said insulating cheeks at their front ends.

30. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 35 sparking plug leads, and a bearing end plate of the machine, covering said insulating cheeks at their front ends.

35. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 40 sparking plug leads, and a bearing end plate of the machine, covering said insulating cheeks at their front ends.

40. In a high tension distributor in magneto-electric ignition machines, in which the distributor rotates vertically above and parallel to the axis of rotation of the rotor of the machine in the same casing of the machine, the combination with the stationary current-collecting brushes, of two removable insulating cheeks in which said brushes are embedded, said insulating cheeks closing both sides of the distributor space, and also containing the insertion apertures and connecting clips or terminals for the 45 sparking plug leads, and a bearing end plate of the machine, covering said insulating cheeks at their front ends.

45. In testimony whereof we have signed our names to this specification.

JACQUES SCHNEIDER.
ERNST HÜRLIMANN
FREDERIC BILLON.
